UNITED STATES PATENT OFFICE

130,303

DESIGN FOR A BERET

Arthur J. Stack, Westport, Conn., and Alys C. Moran, New York, N. Y., assignors to Hat Corporation of America, Norwalk, Conn., a corporation of Delaware

Application June 27, 1941, Serial No. 101,738

Term of patent 3½ years

To all whom it may concern:

Be it known that we, Arthur J. Stack and Alys C. Moran, citizens of the United States, residing, respectively, at Westport, in the county of Fairfield and State of Connecticut, and at New York, in the county of New York and State of New York, have invented a new, original, and ornamental Design for a Beret, of which the following is a specification, reference being had to the accompanying drawing, forming a part thereof, and in which:

Fig. 2 is a side view of the beret shown in Fig. 1.

Fig. 3 is a rear view of the beret shown in Fig. 1.

We claim:

The ornamental design for a beret, as shown.

ARTHUR J. STACK.
ALYS C. MORAN.
